UNITED STATES PATENT OFFICE.

FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY.

FLUID-ACTUATED ROTARY TOOL.

1,385,134.

Specification of Letters Patent. Patented July 19, 1921.

Application filed September 1, 1920. Serial No. 407,504.

To all whom it may concern:

Be it known that I, FRANCIS A. JIMERSON, a citizen of the United States, residing at Athens, county of Bradford, and State of Pennsylvania, have invented a certain new and useful Improvement in Fluid-Actuated Rotary Tools, of which the following is a specification accompanied by drawings.

This invention relates to fluid actuated rotary tools, such as drills, grinders, and the like, but more particularly to such a tool operated by a motor provided with a plurality of radially arranged cylinders having pistons connected to a common crank pin on a longitudinally extending crank, for imparting rotation to a drill, emery wheel or other operative part to be actuated.

The primary objects of the invention are to increase the speed of the machine with a given motor of the type referred to, relieve the crank and connected parts of undue strain, and prolong the life of the crank and other operative parts of the machine.

Another important object is to shorten the motive fluid passages leading to the cylinders as much as practically possible and reduce the clearance required between the cylinders and the tool case.

A further object is to carry the exhaust from the cylinders past the live air ports in a simple and convenient manner which avoids possible interference or leakage between the live and exhaust air ports and passages.

To these and other ends which will appear, the invention consists of the features of construction, arrangement of parts and combinations of elements substantially as hereinafter fully described and claimed in this specification and shown in the accompanying drawings in which—

Figure 1 is a longitudinal sectional elevation of a rotary drill selected as a type of tool to illustrate the invention,

Fig. 2 is a transverse sectional view on the line 2—2 of Fig. 1 looking in the direction of the arrows, and

Fig. 3 is a similar view on the line 3—3 of Fig. 1 looking in the direction of the arrows, which indicate that the view is taken in the opposite direction from that of Fig. 2.

Referring to the drawings, the case A is provided in this instance with an enlarged chamber B at its rearward portion within

and E extend. There may be any desired number of these cylinders arranged singly or in pairs but in this instance I have shown three cylinders for purposes of illustration. The cylinders in this instance are single acting and are preferably removably connected to the case in any suitable or desired manner as by means of cylinder cap screws (not shown). The pistons F reciprocating in the cylinders are provided with suitable connecting rods G suitably connected to a common crank pin H on a longitudinally extending crank J operatively connected by suitable gearing at the front end of the machine to drive the rotary drill bit K carried in the chuck L adapted to be connected to the spindle O.

The supply of motive fluid to the machine is controlled by the usual throttle lever P connected to actuate the throttle valve Q in the handle R which may be connected to the case in any suitable manner as by means of handle cap screws (not shown). Any suitable throttle valve may be provided and as the operation of this valve is obvious and forms no part of the present invention, it will not be further described.

In assembling the connecting rods G on the crank pin H, a connecting rod sleeve S is placed over the crank pin and connecting rod rings T are placed over the ends of the connecting rods and a washer U and crank pin screw V hold the parts on the pin. The crank is preferably provided with an offset extension W to which a counterweight X may be suitably fastened.

The case is provided with a reduced bore Y and the motive fluid supply passage Z in the handle and case leads to an admission port a in said bore intermediate the length of the bore. Motive fluid passages b connect the cylinders with combined supply and exhaust ports c located in the case rearwardly of the admission port a, so that the passages b are as short as conveniently and practicably possible and the necessary clearance between the cylinders and the case is materially reduced. The motive fluid passes alternately in both directions in the passages b for supply and exhaust and by making these passages comparatively short the speed of the motor is increased and better efficiency is obtained. The case A is also provided with an exhaust port d communicating with the smaller bore Y from which

the exhaust passes through the exhaust chamber *e* to the atmospheric port *f*. This exhaust port *d* may be located in any convenient position but is preferably forward 5 of the admission port *a* as a convenient means of bringing the exhaust to the front end of the machine.

A main valve bushing *g* is inserted in the bore *Y* of the case, to form a tight fit and 10 this main bushing *g* is formed with supply ports *h* registering with the ports *c*. The bushing *g* is also provided with an exhaust port *j* at its forward end and an annular passage *k* in the interior of the bushing intermediate the supply ports *h* and the exhaust port *j*, which passage *k* communicates with the main supply passage *Z* in the case.

The crank *J* as shown extends through the main valve bushing *g* and is provided 20 with a hollow bore or portion *o* lying within the bushing *g*. The periphery of the crank is provided with a longitudinal passageway in the form of a groove or depression *p*, adapted to connect the annular groove *k* in 25 the valve bushing *g* successively with the combined supply and exhaust ports *h* so that motive fluid is supplied and distributed to the cylinders of the motor. The crank is also provided with a rearward port *q* co- 30 operating with the ports *h* in the bushing for permitting the cylinders to exhaust into the hollow bore of the crank and thence through the exhaust port *r* to the main 35 exhaust of the machine. By exhausting the cylinders into the interior of the crank and thence to the forward portion of the crank, the exhaust is carried past the live air ports supplying motive fluid to the cylinders but without interference with said ports or with 40 the passages leading thereto and therefrom.

The crank should be a substantially close fit in the valve bushing *g* and in order to take the strain of the rotating parts from the valve bushing, anti-friction bearings are 45 provided for each end of the crank in the case beyond the ends of the bushing. With a high speed motor such as the motor disclosed herein, the bearing construction provided prolongs the life of the crank and 50 valve bushing.

These anti-friction bearings are preferably in the form of ball bearings. The crank end bearing *s* at the inner end is preferably provided with the bearing liner *t*, and the 55 bearing *u* at the forward end of the crank forms both a crank and spindle bearing and is provided with the liner *v*.

The crank is provided with the crank pinion *x* meshing with the gear *y* formed on 60 the spindle *O* and the spindle *O* preferably rotates within the spindle bushing *z* within the gear case 2 suitably secured to the front end of the case *A* as by means of the cap screws 3 or other fastening devices. A spindle bearing stud 4 is supported from the

case *A* within the bushing *5* and carries the ball bearing 6 for the spindle gear *y*. It is however to be understood that any suitable or desirable form of driving connections may be provided between the crank and the spindle, the connections shown having proved satisfactory and efficient for a high speed tool. 70

In the operation of the machine, motive fluid, as air under pressure, is supplied 75 through the supply passage *Z* under the control of the throttle valve *Q* and throttle lever *P*, and the live air passes around the annular passage *k* in the bushing *g*, through the longitudinal groove *p* in the crank to 80 one of the motive fluid passage ways *b* leading to a cylinder. In the drawings, the parts are in such relative positions that admission is about to take place to the cylinder *C* as the drawings are viewed, the cylinder *D* is exhausting through the hollow bore of the crank and the cylinder *E* is at cut-off and on the expansion stroke. As the crank rotates this cycle of operations is repeated in succession for the cylinders. 85 90

I claim:

1. In a rotary tool, the combination of a case, a fluid actuated motor having a plurality of radially arranged cylinders in said case, a forwardly extending crank connected to be driven by said motor and having a hollow portion, a valve bushing in the case over said hollow portion of the crank, a motive fluid supply passage in the case leading to an admission port located at a point intermediate the length of the bushing, motive fluid passages leading from the cylinders to supply ports in the bushing located rearwardly of the said admission port, an exhaust port in the bushing, a peripheral passageway in the crank for controlling the distribution of motive fluid to the passages leading to the cylinders, and ports in the crank for permitting the cylinders to exhaust through the hollow portion of the crank. 100 105 110

2. In a rotary tool, the combination of a case, a fluid actuated motor having a plurality of radially arranged cylinders in said case, a forwardly extending crank connected to be driven by said motor and having a hollow portion, a valve bushing over said hollow portion of the crank, anti-friction bearings in the case for the forward and rearward ends of said crank beyond the ends of the bushing, motive fluid passages in the case 120 leading from the cylinders to supply ports in the rearward ends of the bushing, an exhaust port in the forward end of the bushing, a motive fluid supply passage communicating with an admission port in the bushing located at a point intermediate the said supply and exhaust ports, a passageway in the wall of the hollow portion of the crank for controlling the distribution of motive fluid to the cylinders, and ports in the crank 125 130

for exhausting the cylinders through the hollow portion of the crank.

3. In a rotary tool, the combination of a case having a forwardly extending bore, a fluid actuated motor having a plurality of cylinders radially arranged in the rearward portion of the case, a motive fluid supply passage in the case leading to an admission port at a point intermediate the length of 5 said bore, fluid passages leading from points in said bore located rearwardly of said admission port to the said cylinders, an exhaust port in the case, a valve bushing in said bore having ports registering with said 10 ports in the case, a crank adapted to be driven by said motor and having a hollow portion in said bushing, said crank also having ports and a peripheral passage way for controlling the distribution of motive fluid 15 to the cylinders and for exhausting the cylinders through the hollow portion of the 20 crank.

4. In a rotary tool, the combination of a case having an enlarged rearward chamber 25 and a forward bore of reduced diameter, a fluid actuated motor having a plurality of radially arranged cylinders extending into said rearward chamber and provided with pistons adapted to be connected to operate 30 a crank, said case having a motive fluid supply passage leading to an admission port at a point intermediate the length of said smaller bore, motive fluid passages connecting the cylinders with combined supply and 35 exhaust ports located at points in the smaller bore rearwardly of the said admission port, an exhaust port in said smaller bore, a valve bushing in said smaller bore having ports registering with said ports in the case, a 40 crank having a hollow portion extending through said bushing and provided with a peripheral passage way for controlling the supply of fluid to the cylinders, and also provided with ports for exhausting said

5. In a rotary tool, the combination of a case having an enlarged rearward chamber and a forward bore of reduced diameter, a fluid actuated motor having a plurality of 50 renewable radially arranged cylinders extending into said enlarged rearward chamber, single acting pistons reciprocating in said cylinders and having connecting rods adapted to be connected to a common crank 55 pin, a motive fluid supply passage in the case leading to an admission port intermediate the length of said smaller bore, motive fluid passages connecting the cylinders to combined supply and exhaust ports located rearwardly of the said admission port, an exhaust port at the forward end of said smaller bore, a main valve bushing in said smaller bore of the case having ports registering with said combined supply and exhaust 60 ports, and also having an exhaust port at its forward end and an annular interior passage registering with the said admission port in the case, a crank extending through said main valve bushing and having a crank pin 65 for the connecting rods of the pistons of the motor, bearings for each end of the crank in the case, said crank having a hollow portion lying within the main valve bushing and a longitudinal groove or depression on its periphery adapted to connect the annular groove in the valve bushing successively with the said combined supply and exhaust 70 ports, and also having a rearward port and a forward port communicating with the hollow interior of the crank, for exhausting said cylinders successively through the crank to the exhaust port in the main valve bushing, a spindle, and operative means for driving said spindle from said crank. 75

In testimony whereof I have signed this specification.

FRANCIS A. JIMERSON.
